US0D1092928S

(12) United States Design Patent (10) Patent No.: US D1,092,928 S
(45) Date of Patent: * Sep. 16, 2025

(54) SHOE SOLE

(71) Applicant: Jinjiang Longzu Sports Goods Co., Ltd., Fujian (CN)

(72) Inventor: Chaojie Zeng, Fujian (CN)

(73) Assignee: Jinjiang Longzu Sports Goods Co., Ltd., Quanzhou (CN)

() Term: 15 Years

(21) Appl. No.: 29/985,671

(22) Filed: Jan. 16, 2025

(51) LOC (15) Cl. 02-04

(52) U.S. Cl.

USPC D2/957; D2/947; D2/951; D2/953; D2/954; D2/959; D2/960

(57) CLAIM

The ornamental design for a shoe sole as shown and described.

DESCRIPTION

FIG. 1 is a perspective view of a shoe sole showing my new design;

FIG. 2 is another perspective view thereof;

FIG. 3 is a top plan view;

FIG. 4 is a bottom plan view thereof;

FIG. 5 is a left view thereof;

FIG. 6 is a right view thereof;

FIG. 7 is a front view thereof;

FIG. 8 is a back view thereof;

FIG. 9 is a partial enlarged view of portion 9 in FIG. 2; and, FIG. 10 is a partial enlarged view of portion 10 in FIG. 2. The dash dash lines depict portions of the shoe sole and form no part of the claimed design.

The dot dash line is included for the purpose of illustrating the bounds of the enlarged view and forms no part of the claimed design.

1 Claim, 10 Drawing Sheets
